J. KIEFER,
DEVICE FOR ACTUATING SIGNALS AND THE LIKE,
APPLICATION FILED JULY 21, 1915.
1,273,620. Patented July 23, 1918.

Inventor:
Johann Kiefer,

His Attorney.

UNITED STATES PATENT OFFICE.

JOHANN KIEFER, OF CHARLOTTENBURG, GERMANY, ASSIGNOR TO GENERAL ELECTRIC COMPANY, A CORPORATION OF NEW YORK.

DEVICE FOR ACTUATING SIGNALS AND THE LIKE.

1,273,620.

Specification of Letters Patent.

Patented July 23, 1918.

Application filed July 21, 1915. Serial No. 41,206.

To all whom it may concern:

Be it known that I, JOHANN KIEFER, a subject of the Emperor of Germany, residing at Charlottenburg, Germany, have invented certain new and useful Improvements in Devices for Actuating Signals and the like, of which the following is a specification.

My invention relates to an actuating mechanism for signaling apparatus and particularly to such apparatus as is mounted upon a mast or other support where the same is inaccessible to the operator, and must, therefore, be actuated by means of connections extending some distance from the actuating mechanism, usually to the ground or floor. In devices of this character the light controlling mechanism, such as a shutter, remains either entirely open or entirely closed, or the same may be rapidly opened and closed. Hitherto for this purpose two operating connections extending to the ground have usually been provided, the one for opening the light controlling mechanism and the other for closing the same, which connections had to be actuated alternately and the manipulation of which frequently led to confusion.

In accordance with my invention a single operating connection is provided by means of which the actuating mechanism and through this the light controlling apparatus is operated to one position and at the same time energy is stored which when released actuates the automatic mechanism and through this the light controlling apparatus to assume the opposite position.

Another feature of my invention is the provision of a locking mechanism co-operating with the actuating mechanism so that the latter may be secured in a given position, the locking mechanism being operated and released by the single manually actuated connection.

For a fuller understanding of my invention reference may be had to the accompanying drawings, in which Figure 1 is a side view of the actuating mechanism with a portion of the casing broken away; and Fig. 2 is a plan view showing certain parts in section.

In the drawings 10 is a casing within which is mounted and housed the actuating mechanism. In the embodiment here shown, one end of a shaft 11 is journaled in the

casing and the other end thereof is connected to any suitable light controlling apparatus, such as a shutter. The shaft by its rotation in one direction or the other opens or closes the light controlling apparatus in a manner well known in the art. For the sake of simplicity, therefore, I have not here illustrated the light controlling apparatus. The shaft 11 is surrounded by a spring 12, one end of which is secured to the casing 10 while the other end is secured to the shaft 11, the spring, in the embodiment here shown, being arranged to rotate the shaft in the direction of the hands of a clock and preferably to bring the light controlling mechanism to the open position. A disk 13 is secured on the shaft 11 and is provided with a lug 14 which engages a stop 15 when the light controlling apparatus has been brought to a predetermined extreme position, preferably the closed position. A gear 16 is loosely mounted on the shaft 11, as here shown indirectly by means of a sleeve 17 which extends from the disk 13 and is interposed between the gear 16 and the shaft 11. The disk 13 is connected to the gear 16 by a spring 18 which is relatively stiff as compared with the spring 12. The gear 16 is engaged by a toothed segment 19 which is secured on a shaft 20. A lever 21 is secured without the casing to the shaft 20, and is provided at its outer end with an opening 22 for the reception of one end of a cord or chain (not shown) which extends to a point where the same is accessible to an operator. A disk 23 is secured to or integral with one side of the segment 19. A crank arm 24 is secured on the shaft 20. To the outer end of this crank arm is pivoted an arm 25, the outer end of which is provided with an offset portion carrying a roller 26 which engages the disk 23, the roller being held in engagement with said disk by means of a spring 27. The segment 19 is provided with a notch 28 adapted to receive the detent of a pawl 29 pivoted on a lug 30 projecting from the wall of the casing. The pawl is held in engagement with the segment 19 by a spring 31. A cam 32 is carried on one face of the pawl 29, and its inner end extends toward the disk 23.

When it is desired to manually actuate the light controlling mechanism, for example to a closed position, the operator pulls down the lever 21 which causes the

shaft 11 to rotate in a counter clockwise direction, to put spring 12 under tension and through suitable connections from the shaft 11 to operate the light controlling mechanism. As soon as the lug 14 engages the stop 15 the movement of the sleeve 17 ceases. If the lever 21 is rotated still further the more powerful spring 18 is brought under tension and by the increased resistance offered by this spring the operator is aware that the light controlling mechanism is in a closed position. As soon as the operator releases the lever 21 the actuating mechanism is moved to the other position by the recoil of the spring 12; that is, in the embodiment here shown, to the position in which the light controlling mechanism is open.

Now if it is desired to maintain the light controlling mechanism in a closed position against the action of the spring 12, the lever 21 must be moved still further until the detent on the pawl 29 engages the notch 28. In this manner the spring 18 is put under tension and the actuating mechanism is locked in a position corresponding to the closed position of the light controlling mechanism. In order to release the lock the lever 21 must be moved still further against the tension of the spring 18, which latter is thereby put under increased tension. The roller 26 then rides up over the cam 32 and drops behind the same so that when the lever 21 is released and the roller is returned by the force exerted by the spring 18, the roller engages the rear side of the cam 32 and lifts the detent on the pawl 29 from the notch. For ordinary operation, however, that is, for simply opening and closing the light controlling mechanism, the operator only moves the lever 21 until he is aware, on account of the resistance offered by the spring 18, that the light controlling mechanism is in a closed position.

While my invention is primarily designed for the control of signal lights, it is, of course, equally applicable to the control of semaphores or other signal appliances.

What I claim as new and desire to secure by Letters Patent of the United States, is:—

1. In combination, a movable member, two successively operated energy storing devices of different power connected to said member, means for moving said member against the action of the first energy storing device, and means operative only after the second energy storing device becomes active for locking said movable member against return movement.

2. In combination, a movable member, an energy storing device connected to said member for returning it to its original position, means for moving said member against the action of said energy storing device, a second energy storing device of

greater power than the first interposed between said means and said movable member, and a lock for restraining the movement of said member and becoming operative only after the second energy storing device becomes active. 70

3. In a signaling device, a movable member for actuating the signal, two successively operated energy storing devices of different power connected to said movable member for storing energy when said member is moved, means for limiting the energy storing capacity of the first energy storing device which becomes operative when the signal has been operated, and means operative after the second energy storing device has become active for locking said movable member. 75

4. In a signaling device, a movable member for actuating the signal, two successively operated energy storing devices of different power connected to said movable member for storing energy when said member is moved, means for limiting the energy storing capacity of the first energy storing device which becomes operative when the signal has been operated, means operative after the second energy storing device has become active for locking said movable member, and means actuated in response to a further movement of said second energy storing device for releasing said lock. 80

5. In a signal setting mechanism, a movable member for actuating the signal, a spring connected thereto which is put under tension by the movement of said member, a second stiffer spring connected to said member and put under tension after a predetermined movement of said member, and a lock for restraining the return movement of said member and becoming operative only after said second spring is under tension. 100

6. In a signal setting mechanism, a movable member for actuating the signal, means for moving said member to one position, a tension spring connected to said member for returning the same to its original position, a second spring connected to said member which is put under tension only after a predetermined movement of said member, a lock for securing said member in its moved position and after the second spring has become effective, and means becoming operative after a still further movement of said member for releasing the locking means. 110

7. A mechanism for setting a signal device to two positions, comprising a rotatable shaft for actuating the signal device, a system of gears for rotating the shaft in one direction, a stiff spring intermediate between the gear and the shaft, a lesser spring arranged to be put, under tension by the rotation of the shaft and thereby adapted by its recoil to rotate the shaft in the oppo- 125

- site direction, a stop for limiting the rotation of the shaft in the first direction, means for putting the stiff spring under tension, and locking the gearing and thereby the 5 shaft against rotation in the opposite direction, and means for increasing the tension of the stiff spring and unlocking the gearing, whereby the shaft is released to the recoil action of both springs.
- 10 8. In combination, a movable member, means for moving said member in one direction, an energy storing device connected to said member for restoring the same to its original position, a second energy storing device more powerful than the first connected to said member and operative only 15 after a predetermined movement of said member, and means for locking said member in position after said second energy storing device becomes operative. 20

In witness whereof I have hereunto set my hand this tenth day of June, 1915.

JOHANN KIEFER.
